CLAIM

The ornamental design for an adjustable length headboard stopper, as shown and described.

DESCRIPTION

FIG. 1 is a front, right and bottom perspective view of an adjustable length headboard stopper, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1.

FIG. 10 is another front, right and bottom perspective view of the adjustable length headboard stopper in another state. FIG. 11 is an exploded view of the adjustable length headboard stopper of FIG. 1; and,

FIG. 12 is another front, right and bottom perspective view of the adjustable length headboard stopper in another state. The broken lines shown in the drawings are included for the purpose of illustrating portions of the adjustable length headboard stopper that form no part of the claimed design. In addition, the dot-dash broken lines in FIGS. 1 and 9 depict the boundaries of the enlargements that form no part of the claimed design.
